UNITED STATES PATENT OFFICE.

CLARENCE J. ALDRIDGE, OF SEATTLE, WASHINGTON.

WATER HEATER FOR GAS BURNERS.

Application filed February 4, 1926. Serial No. 86,009.

This invention relates to water heating appliances and particularly to a water heating appliance adapted to be placed upon and coat with the ordinary burner found 5 upon gas stoves.

The main object of my invention is to provide an appliance or attachment of this character embodying a water heating chamber so formed as to rest upon a gas burner 10 and having apertures coinciding with the gas jets of the burner so that cooking utensils may be disposed upon the appliance, the heat from the gas jets being used not only for cooking but also for heating water in 15 the appliance.

A further object is to provide a device of this character whereby water may be quickly heated without interfering with cooking and which may be used in connection with 20 any gas stove.

My invention is illustrated in the accompanying drawings wherein:—

Figure 1 is a vertical sectional view of a water heater constructed in accordance with 25 my invention, the water tank being shown in elevation;

Figure 2 is a horizontal section through the water heater; and

Figure 3 is an underside plan view.

Referring to these drawings 10 designates 30 the body of my appliance which is circular in plan view and may have any desired depth and has the upper and lower plates 11 and 12 and the peripheral wall 13 to provide a water chamber. An inlet nipple or pipe 14 enters the chamber at one point and an outlet nipple or pipe 15 carries water therefrom. The center of the body 10 is preferably provided with a projecting hub 16 35 which is adapted to seat within the central opening or hollow ordinarily found on gas burners and radiating from the center are a plurality of elongated openings 17 adapted to coincide with the gas jets of the burner, these openings, of course, being bounded by radial walls. At the end of 40 each opening there is disposed a small foot 18 which spaces the body from the burner to permit the entrance of air necessary for 45 combustion.

When this device is disposed over a gas burner the jets of gas will be discharged upward through the slots or openings 17 and under these circumstances a cooking utensil 55 may be disposed upon this appliance and the food cooked in the usual manner by the gas

jets, while at the same time the heat from the gas jets will be transmitted to the water in the appliance and thus hot water secured at no extra cost. Preferably there will be one of 60 these appliances disposed in connection with each gas burner and the inlet nipples or pipes of each appliance will be connected to a source of supply for instance, by flexible tubes, and the outlets will all be connected 65 to a single main outlet which may extend to the boiler or other reservoir or the inlets may be connected to the lower end of the boiler and the outlets connected to the upper end of the boiler so that while cooking is 70 being done the water may be heated.

I do not wish to be limited to the particular shape of this device as it may be altered to cause it to conform to the shape of a gas burner. I have illustrated, however, an ordinary form of gas burner and shown my heating appliance as conforming thereto. The device is preferably made of thin sheet metal or it may be otherwise formed. 75

While I have illustrated a pipe 19 extending from the nipple 15 to a tank 20, this pipe being disposed on a level above the heater, this is merely illustrative and intended to show the connection between the tank and the heat as ordinarily this pipe 19 would 80 be disposed on a level below the upper face of the heater so as not to obstruct the use of cooking utensils.

I claim:—

1. A water heater comprising a hollow 90 circular body containing water having upper and lower walls and an outer peripheral wall, the outer wall having an inlet and an outlet, and said upper and lower walls having registering openings, the openings having walls entirely surrounding the same and extending between the upper and lower wall to thereby provide spaces through which gas flames may pass from a gas burner upon which the water heater is disposed, the 100 center of the body being formed to provide a member adapted to rest upon and engage with the center of a gas burner, and the lower wall of the body having downwardly extending feet adjacent the circumference of 105 the body to rest upon the gas burner.

2. A water heater comprising a hollow circular body containing water having upper and lower walls and an outer peripheral wall, the outer wall having an inlet and an 110 outlet, and said upper and lower walls having registering openings, the openings hav-

ing walls entirely surrounding the same and extending between the upper and lower walls to thereby provide spaces through which gas flames may pass from a gas burner upon which the water heater is disposed, the center of the body being extended downward to form a downwardly tapering hub adapted to seat within the hollow center of a gas

burner, and feet on the body adjacent the periphery thereof adapted to rest upon the margin of the gas burner and support the body in spaced relation thereto.

In testimony whereof I hereunto affix my signature.

CLARENCE J. ALDRIDGE.
